INVENTOR.

BY R. B. Sheppard

Victor J. Evans

ATTORNEY.

UNITED STATES PATENT OFFICE.

ROBERT B. SHEPPARD, OF BRADY, TEXAS.

RAIL-JOINT.

1,326,793.

Specification of Letters Patent. Patented Dec. 30, 1919.

Application filed August 11, 1919. Serial No. 316,622.

To all whom it may concern:

Be it known that I, ROBERT B. SHEPPARD, a citizen of the United States, residing at Brady, in the county of McCulloch and State of Texas, have invented new and useful Improvements in Rail-Joints, of which the following is a specification.

This invention relates to improvements in rail joints, and the principal object of the invention is to provide a rest for the ties with means for connecting the splice bars to said rest.

Another object of the invention is to provide extensions on the splice bars which extend downwardly between the ends of the ties and engage the upper face of the rest.

The invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is an edge view of a portion of a track showing my invention in use;

Fig. 2 is a plan view;

Fig. 3 is a cross section.

In these views 1 indicates the ties of a track and 2 the rails thereof. At each joint of the rails I locate my improved joint which consists of a broad flat rest member 3 upon which the ends of the ties rest. The splice bars 4 are each provided with downwardly projecting portions 5 which are spaced apart to receive the ends of the ties between them. These portions 5 are provided with laterally extending parts 5' which extend under the rail and the part 5' of one bar rests upon the like part of the other bar, as clearly shown

in Fig. 3. The lower parts rest upon the 45 upper face of the member 3. The bars engage the upper faces of the ties and are bolted to the rest member by the bolt 6. These splice bars are provided with the flange-engaging portions 7 as usual. Spikes 50 8 may be driven into the ties alongside the splice bars, as shown, to hold the ties to the bars.

It will thus be seen that the rail ends are firmly held together so that it is impossible 55 for one rail end to have movement laterally of the other and the device will also prevent one rail end being moved downwardly in relation to the other by the ties giving under the same. However, the device will permit 60 the rails to expand and contract due to changes of temperature.

It is thought from the foregoing description that the advantages and novel features of my invention will be readily apparent. 65

I desire it to be understood that I may make changes in the construction and in the combination and arrangement of the several parts, provided that such changes fall within the scope of the appended claims. 70

What I claim is:—

1. A device of the class described comprising a rest member for receiving the ends of the ties, splice bars having downwardly projecting portions spaced apart to receive the 75 ends of the ties between them and bolts for connecting the splice bars to the rest member.

2. A device of the class described comprising a rest member upon which the ends of the ties rest, a pair of splice bars having 80 flange-engaging parts and downwardly projecting portions on their lower faces spaced apart to receive the ties between them, bolts connecting the splice bars with said rest member and spikes driven into the ties and 85 engaging the edges of the bars.

In testimony whereof I affix my signature.

ROBERT B. SHEPPARD.
